Attorney

UNITED STATES PATENT OFFICE

ROCCO BLESSO, OF HARTFORD, CONNECTICUT

DESIGN FOR A TRAFFIC SIGNAL

Application filed September 8, 1930. Serial No. 36,904. Term of patent 14 years.

To all whom it may concern:

Be it known that I, Rocco BLESSO, a citizen of the United States, and a resident of Hartford, in the county of Hartford, State of Connecticut, have invented a new, original, and ornamental Design for a Traffic Signal, of which the following is a specification, reference being had to the accompanying drawings forming a part hereof:

Figure 1 is a perspective view of a traffic signal showing my design;

Figure 2 is a side view thereof; and

Figure 3 is an end view.

I claim:

The ornamental design for a traffic signal as shown.

ROCCO BLESSO.
